ABSTRACT

The audio signals are recorded on the two tracks of the tape in phase and the control signals for automatically stopping the main tape and for varying the tapespeed of the endless tape are recorded on the respective tracks so as to be out of phase by 180° , so that the audio signals and the control signals may be derived independently as the summation and difference signals. Therefore the recording capacity of a magnetic tape may be much improved and the speed of the endless or auxiliary tape may be varied in response to the control signals.

SPEED CONTROL SYSTEM WITH CONTROL SIGNALS ON ONE TAPE USED TO CONTROL SPEED OF SECOND ENDLESS TAPE

BACKGROUND OF THE INVENTION

The present invention relates to a magnetic recording and reproducing apparatus and more particularly a device for use with a magnetic recording and reproducing apparatus for automatically controlling the speed of magnetic recording medium.

There has been known a device for use with the conventional magnetic recording and reproducing apparatus in which a track is provided on the magnetic recording medium such as a magnetic tape or magnetic disk so that the speed control signals consisting of pulses of constant period and phase or the speed control signals of predetermined frequencies are recorded on the track and the control signals are detected when the magnetic recording medium is transported so as to vary the transport speed of the magnetic recording medium. However this system must provide an additional track for recording the control signals in addition to the tracks used for recording the information so that the recording capacity or density is inevitably reduced. In case of a magnetic tape used for recording the audio signals, it is impossible to provide this additional track.

To overcome this problem, there has been proposed a system in which the control signals are recorded on the tracks for recording the information. In this case, the control signals must be modulated so that it will not interfere with the information signals, and when the information to be recorded are audio signals, the control signals must be so selected as to have a frequency less than for example 20 Hz which is not audible. This system, therefore, has the distinctive defect that the system becomes very complex because the modulators, filters, discriminators to discriminate the control signals from the audio signals must be incorporated.

The same applicant has proposed the new and improved magnetic recording and reproducing apparatus in the application Ser. No. 87,499, filed on Nov. 6, 1970, entitled "MAGNETIC RECORDING-REPRODUCING DEVICE" by Shozo Moriya, Electrical Engineer, at 480, Manpukuji, Kawasaki-shi, Kanagawa-ken Japan, Shoji Ohta, Electrical Engineer, at 5-8-8, Nishifuna, Funabashi-shi, Chiba-ken, Japan, Yasutaka Iwawaki, Electrical Engineer, at 1-23-2, Ishikawa-cho, Ohta-ku, Tokyo, Japan and Yukio usui, Electrical Engineer, at 8-14-23, Sakurayama, Zushi-shi, Kanagawa-ken, Japan, in which the teaching materials reproduced are also reprinted on an endless auxiliary magnetic tape so that a student imitates the reprinted teaching materials which may be reproduced repeatedly and if necessary he may record his imitated speech or the like on the endless tape so as to compare it with the teaching materials. However, the length of each of the blocks of teaching materials varies while the length of the endless tape is fixed so that the teaching materials are reprinted only one portion of the endless tape or the leading portion of the teaching materials is erased when the block containing these teaching materials is too long to be recorded on the endless tape. That is, it is impossible to precisely reprint one block or section of teaching materials upon the whole length of the endless tape.

Therefore one of the objects of the present invention is to overcome the problems described above.

Another object of the present invention is to provide a device for use with a magnetic recording and reproducing apparatus for automatically varying the speed of magnetic recording medium in which the same information signals are recorded on at least two tracks of a magnetic recording medium in the same phase and the tape-speed control signals are recorded on the respective tracks in anti-phase with respect to each other so that the information signals may be derived as the summation signals while the control signals as the difference signals.

Another object of the present invention is to provide a device for use with a magnetic recording and reproducing apparatus for automatically varying the speed of magnetic recording medium in which the transport speed of an endless magnetic recording medium upon which the information signals on a master recording medium are reprinted is varied in response to the control signals recorded on the information signal recording tracks of the master recording medium which is transported at a constant speed so that the rotational speed of the endless magnetic recording medium, that is the apparent length thereof may be varied depending upon the length of the information signals to be reprinted.

Another object of the present invention is to provide a magnetic recording and reproducing apparatus especially adapted for learning in which upon an endless recording medium are reprinted the teaching materials which are divided into a plurality of sections or blocks having different lengths in recording upon a master magnetic recording medium upon which are also recorded the speed control signals ahead of each of the teaching material blocks or section so that the speed of the endless magnetic recording medium may be varied when the teaching materials are reprinted thereupon, whereby the teaching materials may be reprinted completely on the whole length of the endless recording medium or upon a predetermined length thereof.

SUMMARY OF THE INVENTION

In summary, the audio signals are recorded on the two tracks of the tape in phase and the control signals for automatically stopping the main tape and for varying the tape-speed of the endless tape are recorded on the respective tracks so as to be out of phase by 180°, so that the audio signals and the control signals may be derived independently as the summation and difference signals. Therefore the recording capacity of a magnetic tape may be much improved and the speed of the endless or auxiliary tape may be varied in response to the control signals. As the control signals, the audible signals are used so that they may be reproduced by the conventional tape recorders and separated from the audio signals. Therefore the automatic tape-speed varying device in accordance with the present invention is particularly advantageous for use with the universal type recorders.

The present invention will become more apparent from the following description of the preferred embodiment thereof taken in conjunction with the accompanying drawing.

BRIEF DESCRIPTION OF THE DRAWING

FIG. 1 is a schematic view of a magnetic recording and reproducing apparatus of the type especially adapted for learning and incorporating therein a device

for automatically varying the speed of recording medium in accordance with the present invention;

FIGS. 2A and 2B are for explanation of magnetic tapes used by the apparatus shown in FIG. 1;

FIG. 3 is a diagrammatic view illustrating a device for temporarily stopping the teaching material tape;

FIG. 4 is a block diagram of an electric circuit of the apparatus shown in FIG. 1;

FIGS. 5 and 6 are circuit diagrams of the components incorporated in the block diagram shown in FIG. 4; and

FIG. 7 is a diagrammatic view illustrating a variation of magnetic heads used in the present invention.

DESCRIPTION OF THE PREFERRED EMBODIMENT

The present invention will be described as being applied to a magnetic recording and reproducing device especially adapted for learning (to be referred to as "A TAPE RECORDER" hereinafter for brevity) of the type disclosed in the above application Ser. No. 87,499.

Referring to FIG. 1, reference numeral 1 designates a main body or housing of the tape recorder; 2 and 3, a payoff and takeup reels respectively which are disposed upon the main body 1 and driven by a drive motor (not shown); 4, a magnetic tape recording thereupon the teaching materials in a manner to be described in more detail hereinafter; 5 and 6, tape guides; 7, a capstan; and 8, a pinch roller pressed against the capstan 7 through the tape 4 to transport the same in response to the depression of a playback button as will be described in more detail hereinafter. As shown in FIG. 3, one end of a pinch roller lever 8₁ is pushed toward a plunger magnet P when it is energized so that the pinch roller 8 may be moved away from the capstan 8, thereby temporarily interrupting the transport of the magnetic tape 4. Reference numerals 9 and 10 designate a two-channel erase and record-playback magnetic heads respectively.

As best shown in FIG. 2A, the magnetic tape 4 has two tracks 4₁ and 4₂ upon which are recorded the same one sentence in foreign language as blocks A₁ and A₂ in the same phase respectively. Ahead of the blocks A₁ and A₂ in the respective tracks 4₁ and 4₂ are recorded tape-speed-control signals C_{v1} and C_{v2} in opposite or anti-phase and behind the blocks A₁ and A₂ on the respective tracks 4₁ and 4₂ are also recorded tape-stop signals C_{st1} and C_{st2} in anti-phase or opposite phase. The record-reproduce head 10 comprises in practice two heads 10₁ and 10₂ so as to reproduce the tracks 4₁ and 4₂ respectively of the tape 4.

The control signals C_{v1} and C_{v2} generally consist of the audible frequencies which are varied depending upon the lengths of the blocks of teaching materials to be reproduced after the control signals. In the instant embodiment, three frequencies are used; the first frequency f₂=120 Hz, the second frequency f₃=240 Hz, and the third frequency f₄=480 Hz. For example the frequency f₂ is used as the control signals for the blocks A₁ and A₂ because they reproduce the shorter sentences. As the stop signals C_{st1} and C_{st2} is used a sinusoidal wave of frequency f₁ different from those of the control signals C_{v1}. These control signals f₁-f₄ therefore have the audible frequencies in sinusoidal waveform.

Referring back to FIG. 1, an endless tape 11 for practice is wrapped around four corner-guide rollers 12₁-12₄ and is transported by a capstan 13 and a pinch

roller 14 in the direction indicated by the arrow a. It is noted that the pinch roller 14 is normally pressed against the capstan 13 and the endless tape 11 is pressed against a record-reproduce head 15 and an erase head 16 by a tape pad 17. As best shown in FIG. 2B, the endless tape 11 has also two tracks 11₁ and 11₂ and the upper track 11₁ is used to reprint the teaching materials from the tape 4 whereas the track 11₂ is used to record and reproduce the sentence or speech practiced or imitated by a student. Each of the record-reproduce and erase two-stacked heads comprise in practice two heads 15₁ and 15₂ and 16₁ and 16₂ for the respective tracks 11₁ and 11₂.

Still referring to FIG. 1, reference numerals 18, 19, 20, 21, 22 and 23 designate a record button, a forward button, a reverse button a playback button, a stop button and a repeat button respectively. These buttons except the repeat button 23 are for controlling the tape 4 through a mechanism (not shown) and when the repeat button 23 is depressed, only the endless tape 11 is transported. Reference numeral 24 designates a microphone whose control button 25₁ may be switched among the teaching material tape playback mode (▷), the endless tape playback mode position (Play) and the record mode position (REC) as will be described in more detail hereinafter. Since these pushbuttons 18-23 and the mechanism coupled thereto for controlling the transport of the tape are widely used in the pushbutton type tape recorders and well known to those skilled in the art, no detailed description will be made in this specification. In brief, upon depression of the playback button 21, the motor (not shown) is driven to drive the capstan 7 to transport the tape 4 in unison with the pinch roller 8. Upon depression of the play button 21, a drive motor M₂ to be described hereinafter is energized to drive the capstan 13 to transport the endless tape 11 at a constant speed in unison with the pinch roller 14. That is, upon depression of the playback button 21, both of the tape 4 and the endless tape 11 are transported at predetermined constant speeds and the tape recorder is switched to the playback mode. The teaching materials recorded on the tape 4 are not only reproduced through the loudspeaker S_p but also reprinted upon the endless tape 11.

When the playback button 21 is depressed simultaneously with a reproduce or playback button 18, the tape recorder is switched to the record mode so that the tape 4 is recorded through an input line (not shown).

Upon depression of the forward or reverse buttons 19 and 20, the pinch roller 8 is moved away from the capstan and the drive motor M₁ rotates either the reel 3 or 2 to thereby forward or reverse the tape 4 at high speed as is well known in the art. Upon depression of the repeat button 23, only the motor M₂ is energized to transport only the endless tape 11.

Next referring to FIG. 4 illustrating the block diagram of the electric circuit of the tape recorder, the record-reproduce heads 10₁ and 10₂ are coupled in series to the input terminals of a pre-amplifier 101. A voltage divider consisting of two resistors R₁ and R₂ having the same value are connected across the input terminals of the pre-amplifier 101, and the junction between them and the heads 10₁ and 10₂ are coupled to the input terminals of a control signal amplifier 102.

As shown in FIG. 5, the pre-amplifier 101 comprises a difference amplifier consisting of two transistors Tr₁

and Tr_2 , and the coils of the heads 10_1 and 10_2 are wound in the same direction. The output of the head 10_1 is applied to the base of the transistor Tr_1 through a coupling capacitor C_1 while the output of the head 10_2 to the base of the transistor Tr_2 through a coupling capacitor C_2 . Both of the emitters of the transistors Tr_1 and Tr_2 are coupled to a common emitter resistor R_3 , and the difference output is derived across a load R_4 coupled to the transistor Tr_2 . An equalizer EQ is provided to adjust the output of the difference amplifier, that is the collector output of the transistor Tr_2 to accommodate required output characteristics. The amplifier **102** is substantially similar to the pre-amplifier **101** except that the input terminals are coupled to the junctions between the heads 10_1 and 10_2 and the resistors R_1 and R_2 .

The teaching material block **A**₁ and its control signals Cv_1 and Cst_1 on the track **4**₁ of the tape **4** are reproduced by the head 10_1 while the teaching material block **A**₂ and its control signals Cv_2 and Cst_2 are reproduced by the head 10_2 , but the output signals are derived from the opposite ends of the coils of the heads 10_1 and 10_2 so that they are out of phase by 180° . From the difference amplifier **101**, the difference between the outputs of the heads 10_1 and 10_2 is derived and applied to the equalizer EQ, so that the output of the difference amplifier is given by

$$(A_1 + Cv_1 + Cst_1) + (A_2 + Cv_2 + Cst_2) = \\ (A_1 + A_2) + (Cv_1 + Cv_2) + (Cst_1 + Cst_2).$$

Since the control signals Cv_1 and Cv_2 and Cst_1 and Cst_2 are the same signals, but out of phase by 180° the control signals Cv_1 and Cv_2 and Cst_1 and Cst_2 are cancelled by each other. As a consequence only the summation of the audio signals A_1 and A_2 are derived from the amplifier **101**. Since the audio signals are the same signals and are in phase, $A_1 + A_2 = 2A_1$.

The output signal of the head 10_2 is applied to the amplifier **102** from the junction between the heads 10_1 and 10_2 and the output signal of the head 10_1 is applied also to the amplifier **102** from the junction between the resistors R_1 and R_2 so that the output from the amplifier **102** is given by

$$(A_1 + Cv_1 + Cst_1) - (A_2 + Cv_2 + Cst_2) = \\ (A_1 - A_2) + (Cv_1 - Cv_2) + (Cst_1 - Cst_2).$$

Since the audio signals A_1 and A_2 are in phase, they are cancelled by each other so that the audio signal output becomes zero. However, the control signal are out of phase by 180° so that the outputs of the control signals become

$$(Cv_1 - Cv_2) = 2Cv_1, \text{ and} \\ (Cst_1 - Cst_2) = 2Cst_1.$$

Referring to FIG. 4, reference characters r_{11} and r_{12} designate movable contacts of a relay R_1 to be described hereinafter, and they are made in contact with the fixed contacts a when the relay R_1 is de-energized, but is made in contact with the fixed contacts b when the relay R_1 is energized. The input terminal of a reprint amplifier **103** is coupled to the output terminal of the pre-amplifier **101** so that the bias current is superposed upon the output from the pre-amplifier **101**. The input terminal of a power amplifier **104** is coupled to the movable contact r_{11} whereas the output terminal thereof is coupled to the loudspeaker S_p . The input terminal of a playback preamplifier **105** is coupled to the fixed contact b of the movable contact r_{12} whereas its output terminal to the fixed contact b of the movable contact r_{11} . The input terminal of a record amplifier

106 is coupled to the microphone **24** so as to amplify the output from the microphone and superpose the base current upon the amplified output. Band-pass filters $F_1 - F_4$ are coupled in parallel and connected to the output terminal of the control signal amplifier **102** so as to pass the frequencies $f_1 - f_4$ described above respectively. The output terminals of these filters $F_1 - F_4$ are coupled to waveform reshaping circuits **107**, **108**, **109** and **110** respectively whose output terminals in turn are coupled "1" set terminals of flip-flops **112-115** respectively.

The interconnections among the filters $F_1 - F_4$, the waveform reshaping circuits **107-110**, the flip-flops **112-115**, the relay drive circuits **117-119** and relays

$R_3 - R_5$ are similar so that only one typical interconnection will be described with reference to FIG. 6 illustrating the interconnection among the filter F_2 , the waveform reshaping circuit **108**, the flip-flop **113**, the relay drive circuit **117** and the relay R_3 . The input terminal I_2 of the filter F_2 is coupled to the output terminal of the amplifier **102**. Reference character C_{201} designates a coupling capacitor; R_{201} , R_{202} and R_{204} , bias resistors of an npn type transistor Tr_{201} ; R_{203} , a load resistor thereof; Tr_{202} , an npn type transistor cascade-connected to the transistor Tr_{201} ; R_{205} , a load resistor of the transistor Tr_{202} ; R_{206} , a bias resistor; C_{202} , a bypass capacitor; and C_{203} , a coupling capacitor.

A T-type network comprising capacitors C_{205} and C_{206} , resistors R_{207} and R_{208} and a capacitor C_{206} is connected in parallel with the feedback path from the transistor Tr_{202} to the transistor Tr_{201} . This network is called a twin-T rejection network the impedance of each element of which is so selected to stop the specified frequency f_2 which passes the filter F_2 .

In the reshaping circuit **108** D_{201} and D_{202} denote rectifier diodes; C_{207} , a charging capacitor; R_{213} , a discharging resistor; R_{210} , a load resistor of npn type transistor Tr_{203} ; C_{208} , a capacitor which forms a differentiating circuit together with a resistor R_{211} ; and D_{203} , a rectifier diode. The reshaping circuit **108** comprising these elements rectifies the output of f_2 from the filter F_2 by its rectifier diodes D_{201} and D_{202} to charge the capacitor C_{207} , thereby conducting the transistor Tr_{203} . The output of the transistor Tr_{203} is differentiated by the differentiating circuit R_{211} and C_{208} and applied to the flip-flop **113**.

The flip-flop **113** is a conventional flip-flop comprising transistors Tr_{204} and Tr_{205} , and the collector of the transistor Tr_{204} is coupled to the diode D_{203} .

The relay drive circuit **117** comprises a switching transistor Tr_{206} whose base is coupled to the collector of the transistor Tr_{205} in the flip-flop **113**.

A relay R_3 is inserted between the collector of the switching transistor Tr_{206} and that of the transistor Tr_{205} .

In response to the output of the frequency f_2 from the amplifier **102**, the twin-T network in the filter F_2 consisting of the T-type phase advancing network of the capacitors C_{204} and C_{205} and the resistor R_{208} and the T-type phase lagging network of the resistors R_{207} and R_{208} and the capacitor C_{206} interrupts the negative feedback path from the collector of the transistor Tr_{202} to the emitter of the transistor Tr_{201} in the filter circuit F_2 . As a consequence the amplification degree attained by the transistors Tr_{201} and Tr_{202} in the filter F_2 is increased, and the output of the filter F_2 is rectified by the diode D_{202} and is charged across the capacitor C_{207} .

thereby conducting the transistor Tr_{203} in the waveform reshaping circuit 108. The output of the transistor Tr_{203} is differentiated by the differentiating circuit R_{211} and the capacitor C_{203} and is rectified by the diode D_{203} , thereby reversing the flip-flop 113, that is conducting the transistor Tr_{204} while turning off the transistor Tr_{205} . Therefore the switching transistor Tr_{206} in the relay drive circuit 117 is turned on, thereby energizing the relay R_3 . In summary, the relay R_3 is energized by the output of the frequency f_2 from the amplifier 102 through the filter F_2 , the reshaping circuit 108, the flip-flop 113 and the relay drive circuit 117. Similarly in response to the outputs of frequencies f_1 , f_3 and f_4 from the amplifier 102, the plunger P and the relays R_4 and R_5 are energized respectively.

The twin-T filter networks employed in the filters are well known to those skilled in the art so that the detailed description will not be made, and it is understood that the component elements and impedances in the twin-T filter networks are so selected that the filters F_1 , F_3 and F_4 may have the narrow-band-stop characteristics to stop the frequencies f_1 , f_3 and f_4 respectively.

Reference character S_1 denotes a normally open contact which is closed when the button 25₁ of the remote switch 25 is switched to the tape playback position (►); and S_1' , a contact which is closed upon depression of the playback button 21. Both of the contacts S_1 and S_1' are connected to the DC source E and to the "0" set terminals of the flip-flops 112, 113, 114 and 115 through a waveform reshaping circuit 111. The "1" output terminals of the flip-flops 112-115 are connected to the relay drive circuits 116, 117, 118 and 119 to energize the relays R_1 , R_3 , R_4 and R_5 respectively as described hereinafter with reference to the relay R_3 .

Contacts r_{31} , r_{41} and r_{51} of the relays R_3 , R_4 and R_5 are coupled through governor contacts G_3 , G_4 and G_5 to the motor M_2 for driving the capstan 13 so as to transport the endless tape 11. The rotational speeds of the motor M_2 are selected by the governor contacts G_3 , G_4 and G_5 so as to transport the endless tape 11 at speeds V_1 , V_2 and V_3 . In the instant embodiment, these tape speeds has the following relation:

$$V_1 > V_2 > V_3.$$

The capstan 7 is driven by the motor M_1 to transport the teaching material tape 4. Reference character G_1 denotes the governor contact of the motor M_1 ; S_2 , a contact which is closed when the button 25₁ of the remote switch 25 is switched to the recording mode position (REC); S_2' , a normally open contact which is closed when the repeat button 28 is depressed; and S_3 , a contact which is closed upon depression of the playback button 21. The governors G_1 - G_5 are carried by the shafts of the motors M_1 and M_2 respectively so as to be opened and closed under the centrifugal force. They may be the mechanical governors which are well known to those skilled in the art so that no detailed description thereof will be made in this specification.

Next the mode of operation of the tape recorder of the type described will be described. When the remote switch 25 is switched to the teaching material tape playback mode position (►) and the playback button 21 is depressed, the contact S_1 is closed so that the "0" set signal is applied to the "0" set input terminals of the flip-flops 112-115, whereby they are set to "0." Simultaneously the contact S_3 is closed to drive the motor M_1 to rotate the capstan 7 so that the tape 4 is transported at a constant speed.

When the tape-speed-control signals Cv_1 and Cv_2 ahead of the teaching material blocks A_1 and A_2 are reproduced by the heads 10₁ and 10₂, the difference component is applied to the input terminal of the control signal amplifier 102 while the summation component is applied to the amplifier 101. The output from the amplifier 102 is applied to the filters F_1 - F_4 and only the filter F_2 outputs the signal because the control signals Cv_1 and Cv_2 are the sinusoidal signals of the frequency f_2 as described above. The output of the filter F_2 is applied through the reshaping circuit 107 to the "1" set input terminal of the flip-flop 112 to thereby set it to "1." As a consequence the relay R_3 is energized to close the contact r_{31} and the current is supplied to the motor M_2 by the circuit $E \rightarrow r_{31} \rightarrow G_3 \rightarrow E$ so that the motor M_2 starts to rotate at a rotational speed controlled by the governor contact G_3 . Therefore the endless tape 11 is transported at the high speed V_1 .

The audio signals recorded on the blocks A_1 and A_2 are in phase so that the summation signal component is applied to the pre-amplifier 101. The output from the preamplifier 101 is applied through the contact r_{11} to the power amplifier 104 to be reproduced by the loudspeaker S_p . Simultaneously the output from the amplifier 101 is also applied through the contact r_{12} and the record amplifier 103 to the head 15₁ to reprint the teaching materials A_1 and A_2 on the track 11₁ of the endless tape 11.

The governor contact G_3 controls the tape speed V_1 of the endless tape 11 so that it may transported by a half length thereof when the teaching materials A_1 and A_2 have been reprinted.

The summation of the control signals Cst_1 and Cst_2 reproduced by the heads 10₁ and 10₂ are zero so that the difference signal is applied to the amplifier 102. Therefore, in response to the output of frequency f_1 from the amplifier 102, the relay R_1 is energized through the filter F_1 , the flip-flop 112 and the relay drive circuit 116 so that both of the movable contacts r_{11} and r_{12} are switched to the fixed contacts b . As a consequence the plunger electromagnet P (See FIG. 3) is energized to move the pinch roller 8 away from the capstan 7 thereby temporarily stopping the tape 4.

The endless tape 11 continues to travel at the speed V_1 , and when the endless tape 11 makes on rotation, the reprinted teaching materials may be reproduced through the head 15₁, the contact V_{12} (b), the amplifier 105, the contact V_{11} (b), the power amplifier 104 and the loudspeaker S_p . After the student listens the reproduced teaching materials, he switches the button 25₁ to the record mode position (REC) and imitates the teaching materials he heard before the microphone 24 so that his speech may be recorded upon the lower track 11₂ of the endless tape 11 through the microphone 24, the record amplifier 106, the contact r_{21} (b) and the head 15₂. Since the teaching materials are recorded upon the first half of the track 11₁ as described above, the endless tape 11 makes one rotation when the student's speech was recorded on the track 11₂.

When the button 25₁ is switched to the play mode position, the reprinted teaching materials and his speech are reproduced through the circuit

the playback pre-amplifier 105 → r_{11} → the power amplifier 104 → the loudspeaker S_p . Therefore, the student compares his speech or imitation with the reproduced teaching materials. When the student thinks his practice is not sufficient judging from this comparison, he switches the button 25₁ of the remote switch 25 to the record mode position (REC) again so that he may record his speech again on the track 11₂. Thereafter, he switches the button 25₁ to the play mode position to compare his speech with the teaching materials reproduced from the track 11₁. Therefore it is seen that the student repeats his practice of the same teaching materials as many times as he wishes only by operating the button 25₁ of the remote switch 25.

According to the present invention, the speed of the endless tape is varied in response to the tape-speed control signal recorded ahead of the blocks of teaching materials as well as student's imitation may be recorded within the length of the endless tape 11 without leaving any interval between the reprinted teaching materials and the student's speech recorded. Therefore the practice may be repeated in an efficient manner.

As described hereinabove, according to the present invention, the audio signals are recorded on the two tracks of the tape in phase and the control signals for automatically stopping the main tape and for varying the tape-speed of the endless tape are recorded on the respective tracks so as to be out of phase by 180°, so that the audio signals and the control signals may be derived independently as the summation and difference signals. Therefore the recording capacity of a magnetic tape may be much improved and the speed of the endless or auxiliary tape may be varied in response to the control signals. As the control signals, the audible signals are used so that they may be reproduced by the conventional tape recorders and separated from the audio signals. Therefore the automatic tape-speed varying device in accordance with the present invention is particularly advantageous for use with the universal type tape recorders.

The present invention has been described as being applied to a tape recorder for learning and the audio signals and the tape-speed control signals are reproduced by the same heads, but different heads may be employed. That is, as shown in FIG. 7, the audio signals recorded on the tracks 4₁ and 4₂ are reproduced by the heads 10₁₃ and 10₂₃ whose coils are wound in the same direction and the control signals are reproduced by the heads 10_{1c} and 10_{2c} whose coils are wound in the opposite directions from each other and which are disposed in side-by-side relation with respect to the heads 10₁₃ and 10₂₃. The control signals have been described as having sinusoidal waveforms and being recorded in anti-phase on the respective track, but it is understood that the control signals may be pulses or may have the sawtooth waveforms which are recorded in the respective tracks in opposite phase with respect to each other. In this case, a number of pulses recorded may represent the control signals.

According to the present invention, the tape speed of the endless tape may be varied automatically depending upon the length of the blocks of teaching materials recorded on the tape so that the problem of double recording may be eliminated and the teaching materials and the practice may be recorded on the whole length of the endless tape without leaving any time interval therebetween. Therefore, the student may practice in

an efficient manner without waiting a long time before the practice or teaching materials are reproduced after the teaching materials or practice is reproduced.

We claim:

1. A device for use with a magnetic recording and reproducing apparatus for automatically controlling the speed of magnetic recording medium comprising

first driving means for driving a first magnetic recording medium at a predetermined speed, said first magnetic recording medium having at least two recording tracks upon which the information signal is recorded in the same phase, and upon which the speed control signals are recorded in opposed phase, said speed control signals being of specified different frequencies representing several different speeds being recorded before said information signal in the direction of advance of said magnetic medium when reproducing the information signal; reproducing means for reproducing said information signal and said speed control signals recorded on said two tracks of said first recording medium, said reproducing means reproducing said speed control signals recorded in opposed phase by subtracting one from the other and reproducing said information by adding the information recorded in one track to the information recorded on the other track;

second driving means for driving a second magnetic recording medium consisting of an endless tape at several different speeds, speed control signal discrimination means coupled to said reproducing means for receiving the speed control signals reproduced by said reproducing means, said speed control means being coupled to said second driving means for driving said second magnetic recording medium at a controlled speed in response to said speed control signals reproduced, whereby said second magnetic recording medium may be transported at a speed controlled in response to said speed control signals recorded on said first magnetic recording medium.

2. A device for use with a magnetic recording and reproducing apparatus for automatically controlling the speed of magnetic recording medium as specified in claim 1 wherein

said reproducing means comprises a pair of magnetic heads which are disposed in opposed relation with said first recording medium and whose coils are wound in the same direction around the cores of said heads and connected in series, a pair of impedance elements connected in parallel with said two heads, and an amplifier whose input terminals are connected to the junctions between said two heads and between said pair of impedance elements.

3. A device for use with a magnetic recording and reproducing apparatus for automatically controlling the speed of magnetic recording medium as specified in claim 1 wherein

said speed control signal discrimination means comprises at least two filters which pass specified different frequencies respectively, and switching members actuated by the outputs from said filters, and

said second driving means comprises a drive motor having at least two speed control governors so as to selectively maintain the rotational speeds of said drive motor at one of at least two different prede-

terminated speeds, said governors being connected through said switching member to a power source and to said drive motor, whereby said switching members are selectively actuated in response to the frequencies of said speed control signals recorded on said first magnetic recording medium so as to selectively insert said governors between said drive motor and said power source. 5

4. A device for use with a magnetic recording and reproducing apparatus for automatically controlling the speed of magnetic recording medium as specified in claim 1 wherein 10

said reproducing means includes means for reprinting the reproduced information upon said second magnetic recording medium

5. A device for use with a magnetic recording and reproducing apparatus for automatically controlling the speed of magnetic recording medium as specified in claim 4 wherein

said speed control signal discrimination means includes at least two memory circuits having two states to be reversed in response to said speed control signals, and switching members coupled to said memory circuits so as to be actuated when said memory circuits are switched from one state to the other, and 20

said second driving means includes a drive motor which has at least two speed control governors so as to selectively maintain the rotational speed of said drive motor at one of at least two predetermined different speeds, each of said speed governors being connected through said switching members to said motor and a power source. 30

6. A device for use with a magnetic recording and reproducing apparatus for automatically controlling the speed of magnetic recording medium as specified in 35

claim 1 wherein

said reproducing means includes a first pair of magnetic reproduce heads which are disposed in opposed relation with said first magnetic recording medium and whose coils are wound in the opposite directions with respect to each other and a second pair of magnetic reproduce heads whose coils are wound in the same direction, whereby said first pair of magnetic reproduce heads reproduce said speed control signals while said second pair of magnetic reproduce heads reproduce said information.

7. A device for use with a magnetic recording and reproducing apparatus for automatically controlling the speed of magnetic recording medium as specified in claim 6 wherein 15

said speed control signal discrimination means includes at least two filters which pass specified different frequencies respectively and coupled to said memory circuits respectively, whereby one of said filters selectively outputs in response to the difference between the frequency components of said speed control signals so as to cause one of said memory circuits to change from one state to the other.

8. A device for use with a magnetic recording and reproducing apparatus for automatically varying the speed of magnetic recording medium as specified in claim 6 wherein

said memory circuits are reset in response to the energization of said first driving means.

9. A device for use with a magnetic recording and reproducing apparatus for automatically varying the speed of magnetic recording medium as specified in claim 6 wherein said memory circuits comprise flip-flops.
